UNITED STATES PATENT OFFICE.

SWAN TEVANDER, OF TOLEDO, OHIO, ASSIGNOR TO AMERICAN CAN COMPANY, OF NEW YORK, N. Y., A CORPORATION OF NEW JERSEY.

BAIL-EAR.

No. 922,971.

Specification of Letters Patent.

Patented May 25, 1909.

Application filed February 10, 1908. Serial No. 415,078.

To all whom it may concern:

Be it known that I, SWAN TEVANDER, a citizen of the United States, residing in Toledo, in the county of Lucas and State of Ohio, have invented a new and useful Improvement in Bail-Ears, of which the following is a specification.

My invention relates to improvements in bail ears for sheet metal cans or vessels.

10 The object of my invention is to provide a bail ear of a simple and efficient construction, which may be cheaply manufactured and readily applied and securely attached to the top, breasts or other parts of the sheet metal cans or vessels.

My invention consists in the means I employ to practically accomplish this object or result as herein shown and described.

15 In the accompanying drawing forming a part of this specification, Figure 1 is a side elevation of a sheet metal can provided with my invention. Fig. 2 is an enlarged detail section on line 2—2 of Fig. 1. Fig. 3 is a section on line 3—3 of Fig. 2. Fig. 4 is a detail 20 view of the bail ear. Fig. 5 is a detail plan view of one of the attaching washers and Fig. 6 is a detail section showing the parts after they are assembled but before they are 25 forced snugly together preparatory to the galvanizing, sweating, soldering or other operation. Fig. 7 illustrates a modification.

30 In the drawing, A represents a sheet metal can or vessel having a dome shaped top or breast B, furnished with slots b through which the bail ear is inserted, and C the bail.

D D¹ are washers, one fitting inside and one 35 outside the breast or other part of the can to which the bail ear is to be attached, and each furnished with a slot d through which the bail 40 ear F is inserted. The bail ear F has at its inner end shoulders f to engage the inner washer, and in order to cause the bail ear when inserted through the washers D D¹ and the breast or part of the can to which it is to 45 be applied to hold or clamp these parts snugly together so that they may be all firmly united together by the subsequent galvanizing operation, sweating operation or soldering operation, as the case may be.

50 I prefer to provide the upper washer with inclined lips d¹ adjacent to the slot d, which, when the parts are snugly compressed together, are caused to pinch and forcibly grip the shank portion f¹ of the bail ear and thus

snugly and rigidly clamp it in close contact 55 with the breast of the vessel and all the parts in close contact with each other pending the soldering or galvanizing operation. These gripping lips d¹ on the outer washer when the parts are firmly compressed together by the 60 assembling dies tend to straighten out, as illustrated in Fig. 3, and thus in effect narrow the slot in the outer washer through which the shank of the bail ear extends.

The gripping and holding action of the inclined lips d¹ on the flat shank portion f¹ of the washer D will be readily understood from Figs. 3, 5 and 6 of the drawing, Figs. 5 and 6 showing the inclined lips d¹ before the parts are forcibly pressed together and the inclined 70 lips d¹ straightened out so as to pinch the flat shank f¹ between them by a kind of toggle action, as shown in Fig. 3, where all of the parts are forcibly pressed together and the inclined 75 lips d¹ straightened or partially straightened out.

In the modification illustrated in Fig. 7, the upper part of the flat shank f¹ above the outside washer D is illustrated as being 80 slightly upset so as to form shoulders at the narrow edges of said shank f¹ to engage the outer washer D, and thus hold the parts D, D¹, B and F all in close snug engagement 85 with each other so that they will properly fusibly unite when subjected to the galvanizing, sweating or soldering operation, and thus form a liquid tight closure at the bail ears. In this Fig. 7 modification, the inclined lips d¹ on the washer D may be omitted.

I claim:—

1. The combination with a sheet metal vessel having a breast furnished with slots through the same, of slotted washers fitting inside and outside said breast, and bail ears having flat shank portions inserted through 95 the slots of said breast and of said inside and outside washers, and having shoulders engaging the inside washers the outer washer having inclined gripping lips engaging the opposite flat faces of said bail ear shanks to 100 hold said parts in snug engagement with each other, said parts being all fusibly united together, substantially as specified.

2. The combination with a sheet metal vessel having a breast furnished with slots through the same, of slotted washers fitting inside and outside said breast, and bail ears having flat shank portions inserted through 105

the slots of said breast and of the inside and outside washers, and having shoulders engaging the inside washers, said parts being all fusibly united together, and the outer washers having gripping devices engaging the flat faces of the shank portions of the bail ears to hold the parts in assembled position, substantially as specified.

3. A bail ear furnished with a shoulder, 10 and a flat shank portion adapted to be inserted through a slot of a vessel and inner and outer slotted washers through which the shank of the bail ear passes said outer washer and said flat shank having interengaging devices to hold said parts in snug engagement,

and said parts being all fusibly united together, substantially as specified.

4. A bail ear having a flat shank, inner and outer washers through which the shank of the bail ear is inserted, said bail ear being 20 provided with a shoulder engaging the inner washer, and the outer washer having gripping lips to engage the shank of the bail ear and clamp and hold the washers in place, substantially as specified.

SWAN TEVANDER.
